UNITED STATES PATENT OFFICE.

MAURITZ C. INDAHL AND AMOS L. KNIGHT, OF PHILADELPHIA, PENNSYLVANIA,
ASSIGNORS TO LANSTON MONOTYPE MACHINE COMPANY, OF PHILADELPHIA,
PENNSYLVANIA, A CORPORATION OF VIRGINIA.

GALLEY MECHANISM FOR TYPE-COMPOSING MACHINES.

1,149,198.

Specification of Letters Patent. Patented Aug. 10, 1915.

Application filed March 12, 1914. Serial No. 824,234.

To all whom it may concern:

Be it known that we, MAURITZ C. INDAHL and AMOS L. KNIGHT, citizens of the United States, residing at Philadelphia, in the county of Philadelphia and State of Pennsylvania, have invented certain new and useful Improvements in Galley Mechanisms for Type-Composing Machines; and we do hereby declare the following to be a full, clear, and exact description of the same, reference being had to the accompanying drawings, forming part of this specification, and to the figures and letters of reference marked thereon.

This invention relates to galley mechanism for automatic type composing machines in which the type are first set up in lines and the latter assembled in column form in a galley. Prior galley mechanisms, while adequate to deal with ordinary type, were incompetent to handle matter containing certain kinds of what are known as mushroom type, *i. e.*, type whose head extends beyond and overhangs the body in a point or column-wise direction above the line, owing to the fact that when the line transferrer by which the assembled line is shifted into the galley is adjusted to advance the line a sufficient distance to carry the overhang beyond the galley blade so as to permit the latter to return to position at one side of the line assembling channel, the same motion when directed against the supporting quads of the following line would carry the latter and deposit it to such a distance beyond the galley blade as to deprive it of the support necessary to prevent squabbling when the line transferrer is retracted and the galley blade returned to normal position preliminary to the assembling of the next line. In other words, the movement of the line necessary to carry mushroom type free of the galley blade deprives the latter of its supporting function when applied to type of the same point size without the overhang.

The principal object of the present invention is to correct this defect and this is accomplished by the addition of an auxiliary supporting blade adapted to be projected in rear of the galley blade and engage the bodies of the type below the overhang.

A further object is to provide means for adjusting both the galley blade and the line

transferrer, to adapt the machine for both standard and larger sizes, and to deal with either mushroom or ordinary type, the purpose, in this respect, being to increase the capacity of the machine.

In the accompanying drawings illustrating a preferred form of embodiment of the invention, Figure 1 is a top plan view of a galley mechanism with the improvements applied thereto; Fig. 2 is a rear perspective of the galley blade with the auxiliary supporting blade; Fig. 3 is a sectional view showing the galley blade elevated and the line transferrer advanced to deposit a line of mushroom type in the galley; Fig. 4 is a sectional view showing the line transferrer in retracted position and the galley blade depressed to form the line assembling channel with the auxiliary blade projected to support the mushroom type; Fig. 5 is a perspective view on an enlarged scale of the galley blade with auxiliary blade removed therefrom; Fig. 6 is a rear perspective of the auxiliary blade detached. Fig. 7 is a perspective of the removable interponent for the auxiliary blade; Fig. 8 is a top plan view showing the galley blade adjusting devices in different positions of adjustment; Fig. 9 is a detail sectional view of the adjusting interponent for the line transferrer; Fig. 10 is a top plan view of a portion of the line transferrer actuating lever showing the means for sustaining the interponent in adjusted position; Fig. 11 is a perspective view of the line transferrer interponent.

The same numerals designate like parts in the several views.

For purposes of illustration the invention is shown in connection with a galley mechanism constructed in accordance with application Serial No. 824,179 filed March 12, 1914, but is equally applicable to the corresponding mechanism of Patent No. 674,375 dated May 21, 1901. It will suffice for present purposes to designate some of the principal performing members of said prior structures, such as the line assembling channel 1 extending between the horizontally movable line transferrer 2 and the vertically movable galley blade 3, the latter normally closing the entrance to the galley 4 and carried by a vertically movable post 5; the line carrier 6 and opposed type support 7 movable longitudinally of the line channel and

between which the composed line is moved from its place of assembly into register with the galley entrance; and the actuating mechanism for the performing members including cam head 8, lever 9 and compression coupling 10 through which motion is transmitted to the line transferrer. The starting of the galley mechanism may be effected either through the signal controlled mechanism of Patent No. 674,375 or the line actuated trip mechanism of application Serial No. 824,179 the latter being indicated in the drawings. As a rule the overhang or extension of the head of these mushroom type is in a direction above the line, as illustrated at 11, in Figs. 3 and 4 so that when delivered to the type assembling channel 1, the latter set to the width of the body, the head projects over the line transferrer. Moreover, in order to afford adequate support for the extended head, a quad 12 must be provided in the next succeeding line opposite and in position to be entered beneath the overhanging portion of the head. The galley blade 3 operates as a support for the last line in the column to prevent displacement or squabbling during the return movement of the line transferrer and preliminary to the entrance of the next succeeding line, and it is particularly desirable to preserve this function when dealing with mushroom type, that they may be upheld to receive the supporting quads of the next succeeding line. Owing to the extensions of the heads of the type, it is obvious the throw of the line transferrer must be correspondingly increased or adjusted, to the end that the extension may pass beyond the path of the galley blade as in Fig. 3, so that the descent of the latter, after the line has been deposited in the galley, shall not be interrupted or the type broken. But this increased throw of the line transferrer is likewise operative upon the following supporting quads 12 and results in carrying the line containing said quads so far beyond the galley blade as to practically destroy or annul its supporting function, thus leaving the type of the last line without any support on one side and in condition to be easily displaced. To overcome these difficulties and at the same time preserve the functions of the mechanism as a whole for dealing with ordinary type, the movable galley blade is provided or equipped with an auxiliary supporting member or surface adapted to engage the bodies of the type below the extension and capable of withdrawal, when the galley blade is elevated, to permit the entrance of a new line into the galley; and the operating mechanism of the line transferrer is equipped with means for varying its position relatively to the actuating devices or cam with a view to effecting an extension of the stroke of the line trans-

ferrer without altering its position of rest or changing its actuating cam. With these ends in view the following changes and additions have been made in or to the machine as illustrated in the application and patent hereinbefore referred to. A somewhat thicker galley blade is employed and its rear face is recessed as indicated in Fig. 5 to receive the auxiliary line supporting section in the form of a supplemental blade 13 pivotally supported at or near its upper edge upon the main section or galley blade proper.

As the point dimensions of mushroom type is sometimes greater than that for which commercial machines are adapted and beyond the capacity of the adjusting devices applied to the line transferrer for opening the line channel, means are supplied for effecting lateral adjustment of the galley blade, to which end the pin 5^a on the post 5 to which the galley blade is applied instead of being concentric, as heretofore, is eccentrically disposed and is provided with a stop plate 15 adapted to contact with the galley blade head, to limit the rotation of post 5 in opposite directions corresponding to the maximum and minimum throw of the eccentric. Thus by rotating post 5 the position of the galley blade can be changed from normal to abnormal, and vice versa, the normal corresponding with the adjustment for ordinary composition work, and the abnormal corresponding with the larger sizes when casting without composition or as a sorts caster.

When composing ordinary type supplemental blade 13 retains its position flush with or slightly within the rear face of the galley blade which latter operates as heretofore; but when mushroom type are to be operated upon an interponent 16 is inserted between the frame and an arm 17 on supplemental blade 13 in position to engage and tilt the latter on its supporting pivots and cause its lower edge to be protruded beneath the overhang of the type heads into contact with the body portion, Fig. 3. The support thus provided continues while the galley blade is lowered during the assembling of the next line, and when the galley blade rises to admit the next line the overhanging portions of the heads are supported during the rise of the galley blade while blade 13 recedes within its containing recess to pass said overhang.

When the line of supporting quads 12 is forced into the galley it is carried to the same distance as the mushroom type by virtue of the engagement of the line transferrer with the body portion of said type, with the result that upon the return of the line transferrer and descent of the galley blade the last line will stand at a distance from the rear face of the latter equal to or

exceeding the projection of the overhang. This distance is bridged, however, by supplemental blade 18 which is again projected into supporting position by contact 5 with interponent 16. The interponent is preferably in the form of a removable block provided with sustaining pins 18 adapted to enter holes in the frame and is properly proportioned to effect the desired degree of 10 protrusion.

The setting of the line transferrer for dimensioning the line channel is effected as usual through adjustment of the back stop 19 of cam lever 9; but this does not vary 15 the maximum forward position of the line transferrer as measured by the cam.

To vary the forward position and at the same time preserve the timing, the bearing 20 against which the cam acts, instead of 20 being made integral with lever 9, as heretofore, is carried by a supplemental lever 21 pivotally connected to lever 9 at one end, with its opposite or free end in position to engage any one of a series of stepped bearings 22 on an interponent 23, mounted on 25 lever 9. Interponent 23 is attached to lever 9 in a manner to permit adjustment to present either of the steps 22 opposite lever 21, a convenient arrangement for the purpose 30 being shown, the same including a bolt or pin 24 carried by the interponent and riding in a slot 25 in lever 9. Bolt 25 is provided with a sleeve 26 whose inner or engaging end is tapered or rounded to fit in 35 either of a series of seats 27, each of the latter corresponding to one of the steps 22, and means, such as a spring 27, is applied to hold the sleeve in adjusted position.

As thus constructed interponent 23 furnishes a ready means for varying the position 40 of the line transferrer in its relation to the actuating cam without disturbing its relation to the back stop 19, so that the extent of motion of the line transferrer can be 45 varied without disturbing its relation to the line channel when the galley mechanism is at rest to receive the type for a new line.

It should be noted that the bearing 20 for lever 9 does not ride in contact with the 50 entire periphery of the cam, but is merely engaged by a protuberant portion thereof, hence the length of the stroke of the line transferrer can be varied by varying the extent of contact.

Having thus described our invention what 55 we claim as new and desire to secure by Letters Patent of the United States, is:

1. In a galley mechanism such as described and in combination with the movable galley blade thereof, a supplemental type supporting blade carried by and adapted to be projected rearwardly of said galley blade.

2. A galley mechanism provided with a 60 movable galley blade and a transversely

movable line transferrer, and in combination therewith, a supplemental type supporting blade located in rear of and carried by the galley blade and means for moving the supplemental blade rearwardly of 70 the galley blade.

3. In a galley mechanism such as described, the combination with the movable line transferrer forming one wall of the line assembling channel, of an opposed movable galley blade, a supplemental blade located in a recess in the rear face of said galley blade with its outer face normally flush with the rear face thereof but adapted to be projected therebeyond. 75

4. In a galley mechanism provided with a movable galley blade and in combination therewith a supplemental blade supported in a recess in the rear face of the galley blade and adapted to be projected rearwardly therefrom. 80

5. In a galley mechanism provided with a movable galley blade and in combination therewith an auxiliary type supporting member disposed in rear of the galley blade 90 and movable rearwardly therefrom.

6. In a galley mechanism equipped with a movable galley blade, and in combination therewith, a supplemental blade pivotally supported to swing outward from the rear 95 face of said galley blade, and an interponent engaged by the supplemental blade during the downward or closing movement of the galley blade.

7. In a galley mechanism such as described and in combination with the movable galley blade thereof, a revolute and longitudinally reciprocating supporting post provided with an eccentrically located pin for the reception of said galley blade. 100

8. In a galley mechanism such as described and in combination with the movable galley blade thereof, a revolute and longitudinally reciprocating supporting post provided with an eccentric supporting 110 pin and a stop for limiting its rotation, said stop engaging the galley blade head when on said eccentric pin.

9. In a galley mechanism such as described, provided with a line assembling 115 channel formed in part by a vertically movable galley blade and a horizontally movable line transferrer disposed in parallel relation, and in combination therewith, an auxiliary line support located in rear of 120 the galley blade and movable rearwardly thereof, means for actuating said auxiliary line support, and means for adjusting the throw of the line transferrer to effect delivery of the line at various points in rear 125 of the galley blade when elevated.

10. In a galley mechanism such as described and in combination with the movable line transferrer thereof and its actuating cam, transmission devices including an ac- 130

tuating lever, a back stop therefor, a cam engaging member pivotally connected to said actuating lever, and an adjustable stepped interponent carried by the actuating lever 5 in position to be engaged by said cam engaging member.

11. In a galley mechanism such as described, the combination of the following elements, to wit: a vertically movable and 10 laterally adjustable galley blade; a line support located and movable in rear of the galley blade; a line transferrer disposed in parallel with the galley blade and movable

laterally thereof to discharge successive lines of type past the galley blade when elevated; and actuating mechanism for said line transferrer including a cam and adjustable transmitting devices for varying excursions of the line transferrer with relation to its line delivering position. 15
